Inventor:

John McDermott

UNITED STATES PATENT OFFICE.

JOHN McDERMOTT, OF SAN FRANCISCO, CALIFORNIA, ASSIGNOR TO GEORGE E. HARPHAM, OF SAME PLACE.

SHELL-EXTRACTOR.

SPECIFICATION forming part of Letters Patent No. 290,255, dated December 18, 1883.

Application filed March 14, 1883. (No model.)

To all whom it may concern:

Be it known that I, JOHN McDERMOTT, of the city and county of San Francisco, and in the State of California, have invented certain new and useful improvements in shell-extractors for the extraction of exploded or corroded shells from breech-loading guns; and I do hereby declare that the following is a full, clear, and exact description thereof, reference being had to the accompanying drawings, and to the letters of reference marked thereon, making a part of this specification.

My invention relates to the extraction of exploded metal shells from breech-loading guns.

It consists in a novel construction of certain devices or apparatus, in combination with the ramrod of the gun, or other rod, for the purpose of forcing exploded metal shells or corroded shells out of the breech of the gun. For guns using different-sized shells, different-sized extractors must be used.

Figure 1 shows a view of the center wedge of the shell-extractor with a spiral spring on it, and a sectional view of the body. Fig. 2 shows a side view of the shell-extractor. Fig. 3 is a sectional view of the extractor on the plane X of Fig. 1. Fig. 4 is a sectional view of the extractor on the plane Y, Fig. 1. Fig. 5 is a view of the center wedge. Fig. 6 is a view of the body of the extractor.

Like letters have reference to the same parts.

My shell-extractor is constructed of the circular steel tube or body A, with one or more serrations, (three to six is best,) E, running entirely around the upper part, except where cut by the slots H and H'. A solid circular steel wedge, B, with the head F, tapering from the head F to just below the pin D, and from this point being somewhat smaller and of a uniform diameter to the end, is placed in the center of the body A. Upon the lower part of the wedge B is placed a spiral spring, C, which can be dispensed with, if desired. A pin, D, is run through the wedge B at the lower end of the tapering part.

In a breech-loading gun where the metal shells used are two and one-eighth inches in length and one-half inch in exterior diameter at the top, and the metal is one sixty-fourth of an inch in thickness, the following is a description of a shell-extractor for such guns.

For the extraction of exploded or corroded shells in these guns, the body A of my extractor should be two and one-eighth inches in length and the outside diameter should be 55 three-eighths of an inch, and the metal one-eighth of an inch in thickness at the lower end. It should be divided, from the top down to within one-half inch of the bottom, into four equal parts by slots H and H', of about one 60 sixty-fourth of an inch in width, except that the lower part of the slots H' for one inch should be one-eighth of an inch in width, to admit of the working up and down therein of the pin D. At the top of the body A, and extending the whole way around, except where cut by the slots H and H', are placed one or more serrations, E, (three are shown in the drawings, and is the best,) which are one-eighth of an inch apart, and at the highest point are 70 one sixty-fourth of an inch higher than the remainder of the body A, and slope down to the next row below. The interior diameter of the body A, from the bottom up, for the first half inch, should be one-eighth of an inch. 75 At this point the interior diameter is increased to six thirty-seconds of an inch. From this point the interior diameter should increase uniformly, until at the top the interior diameter is two-eighths of an inch. The center 80 wedge, B, is circular in form and two and one-eighth inches in length. For the lower inch the diameter is uniform, and is seven-sixty-fourths of an inch. At a point an inch from the bottom of the wedge B the diameter is increased to three-sixteenths of an inch, so as to 85 form a shoulder. From this point the diameter increases uniformly to the head F which is one-fourth of an inch long. The diameter of the wedge B where it joins the head F is 90 three-eighths of an inch. The head F is fourteen thirty-seconds of an inch in diameter. Upon the lower part of the wedge B is placed a spiral spring, C, of brass or other suitable material, seven-eighths of an inch in length, 95 and fitting closely to the wedge B, and adapted to work in the body A. It can be omitted, if desired. The pin D should be about seven sixty-fourths of an inch in diameter, and just long enough to reach to the outside of the 100 body A, passing through the slots H', and passing through the center of the wedge B to

prevent the wedge B from separating from the body A when not in use.

The extractor, when completed as herein-before described, is dropped into the exploded cartridge-shell in the gun through the barrel, with the top toward the muzzle; or, if the end of the shell is blown off, it may be pushed up through the breech until it is within the exploded shell. The breech of the gun is then closed, and with the ramrod or other rod the wedge B is driven into the body A, forcing the upper ends, containing the serrations E, apart until the serrations E are either forced through the metal of the shell or firmly fastened therein. The breech is then opened, and by a few blows the shell is driven out of the gun. Two or three blows with the ramrod are usually sufficient to fix the serrations E of the extractor firmly enough in the shell, so that it can be driven out; but if the shell sticks very badly it may be necessary to force the serrations entirely through the shell. The serrations E should be as high, but never higher, than the thickness of the metal of the shell to be extracted, and the upper edge or end of the serration should be perpendicular to the body A. For guns carrying larger or smaller shells the extractor should be proportionately increased or reduced in size.

I am aware that there is now in use a shell-extractor consisting of a hollow steel tube cut into four equal parts to nearly the bottom, and having a shoulder extending around the top, which is intended to catch the top of the shell;

and thus drive it out of the gun; but with this extractor it sometimes happens that in the discharge of the gun the top of the shell is forced so close to the barrel that the shoulder of the extractor will not catch on the shell, but slips through it, and the shell must be extracted by other means. With my extractor this is impossible, as it works within the shell, and the wedge B in any case will force the serrations E of the body A into or entirely through the shell.

I do not desire to restrict myself to any particular number of rows of serrations at the top of the body A. I have shown three in the drawings, and consider that number to be the best.

Having thus described my invention, what I claim as new, and desire to secure by Letters Patent, is—

The combination, in a shell-extractor, of a tubular slotted body having one or more rows of serrations at the top, with smooth surface, except at the top, and an expansion circular tapering wedge having a head adapted to receive blows from a ramrod, substantially as herein described, to operate as herein set forth.

In testimony that I claim the foregoing I have hereunto set my hand this 3d day of March, 1883.

JOHN McDERMOTT.
